(57) **CLAIM**

The ornamental design for a pet treat, as shown and described.

DESCRIPTION

FIG. 1 is a front, top and right side perspective view of a first embodiment of a pet treat, according to the new design; FIG. 2 is a right side elevation view thereof;

FIG. 3 is a front elevation view thereof;

FIG. 4 is a top plan view thereof;

FIG. 5 is a bottom plan view thereof;

FIG. 6 is a cross-sectional view thereof, taken along line 6-6 of FIG. 4;

FIG. 7 is a front, top and right side perspective view of a second embodiment of a pet treat, according to the new design;

FIG. 8 is a front elevation view thereof, the back, right side, and left side elevation views being identical thereto;

FIG. 9 is a top plan view thereof;

FIG. 10 is a bottom plan view thereof; and,

FIG. 11 is a cross-sectional view thereof, taken along line 11-11 of FIG. 9.

The smaller stippled shading and larger stippled shading shown in FIGS. 6 and 11 represent a contrasting appearance. The broken lines shown in FIGS. 1, 3, 5-8, and 10-11 illustrate portions of the pet treat that form no part of the claimed design. The break lines shown in the middle portions of the pet treat in FIGS. 7, 8 and 10-11 indicate that the appearance of any portion of the article between the break lines forms no part of the claimed design.
